UNITED STATES PATENT OFFICE.

CLARENCE S. SNAVELY, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

LIGHT-SIGNAL.

1,298,809.

Specification of Letters Patent.

Patented Apr. 1, 1919.

Continuation in part of application Serial No. 175,611, filed June 19, 1917. This application filed July 29, 1918. Serial No. 247,179.

To all whom it may concern:

Be it known that I, CLARENCE S. SNAVELY, a citizen of the United States, residing at Pittsburgh, in the county of Allegheny and 5 State of Pennsylvania, have invented certain new and useful Improvements in Light-Signals, of which the following is a specification.

My invention relates to optical apparatus, and more particularly it pertains to light 10 signals adapted for use in railway signaling.

The present application is a continuation 15 of my co-pending application filed June 19, 1917, Serial No. 175611 for light signals, in so far as the subject matter common to the

two is concerned.

One object of my invention is the provision 20 of a signal capable of projecting in one common direction from one common area, a plurality of beams of light differing in color, from a plurality of different sources. A further object of the invention is the provision 25 of a signal of this character in which a beam of parallel rays is projected from each source of light, and in which the parallelism of each beam is maintained throughout the signal, thus avoiding the necessity for a condensing or objective lens.

Briefly stated, a signal embodying my invention comprises a plurality of sources of light, and means for projecting parallel rays 30 of light from each source to a common area, the rays from the several sources differing in color. Located within the common area is a light deflector which is constructed to project the beams from all of the sources in one 35 common direction so that each beam is visible from one and the same point external to the signal, thus providing for a plurality of color indications from a single area. The 40 light deflector may be of any suitable type, and for any given type the particular construction of this deflector will depend upon the number of sources of light which are provided in the signal. The basic principle will 45 be the same in any instance, however, this principle being that the parallelism of the rays from each source of light is maintained throughout the signal; that is, the rays in each beam are parallel when they reach the 50 light deflector, and continue to be parallel after the beam is deflected by this device.

I will describe two forms of signals em-

bodying my invention, and will then point out the novel features thereof in claims.

In the accompanying drawings, Figure 1 55 is a view showing one form of light signal embodying my invention, the signal shown in this view comprising a refracting device as the light deflector. Figs. 2, 3 and 4, are fragmentary views of the refracting device 60 L shown in Fig. 1, illustrating the manner in which the luminous rays from each lamp are projected to and through this device. Fig. 5 is a view showing in rear elevation the refracting device L which is shown in section 65 in the preceding views. Fig. 6 is a view showing a modification of the signal shown in Fig. 1, and also embodying my invention, the signal shown in this view comprising a reflecting device instead of a refracting de- 70 vice as the light deflector. Figs. 7 and 8 are fragmentary views of the reflecting device L^a shown in Fig. 6, illustrating the manner in which the rays from the light sources are deflected and projected by this device. Fig. 9 75 is a view showing in front elevation the reflecting device L^a which is shown in section in Fig. 6.

Similar reference characters refer to similar parts in each of the several views. 80

Referring first to Fig. 1, the signal in the form here shown comprises three incandescent lamps G, Y and R, and a light deflector L in the form of a refracting device. For each lamp I provide a pair of lenses K, K' 85 arranged to project a beam of parallel rays from the lamp to the device L. These beams are caused to differ in color by any suitable means, such, for example, as by coloring one of the lenses for each lamp. The beams projected from the lamps G, Y and R may, for instance, be made green, yellow and red, re- 90 spectively.

As here shown, the front side of the refracting device L is smooth or plane, while 95 the reverse or rear side is formed at regular spaced intervals with parallel pairs of oppositely inclined surfaces P and P' which extend transversely across the device, the intervening surfaces P² between adjacent pairs of 100 surfaces P and P' being parallel to the surfaces P and P' being parallel to the surface of the front side of the device so that beams of light striking such surfaces P² are not refracted. The surfaces P and P' when

- considered in conjunction with the front or plane side of the device constitute reversely disposed prisms and will be hereinafter referred to as such.
- 5 When lamp Y is illuminated, the rays therefrom which strike the surface P^2 of the refracting device L will pass directly through the device without deflection, but the rays which strike the surfaces P and P' will be 10 refracted substantially as indicated by the dash lines in Fig. 3. The signal is so positioned that the rays from lamp Y which pass directly through the device L without refraction, and which are shown in solid lines 15 in Fig. 3, are projected toward the point or points from which the indications given by the signal are to be observed. The rays which are projected in this direction may aptly be termed the useful rays.
- 20 Assume now that lamp Y is extinguished and lamp G illuminated. The prisms P are so designed that the rays from lamp G striking thereon are deflected and are projected in the same direction as were the useful rays 25 from lamp Y, as shown by the solid lines in Fig. 2; the remaining rays from lamp G are projected in other directions as indicated by the dash lines in this view. Similarly, when lamp R is illuminated (Fig. 4), the rays 30 therefrom which strike prisms P' , and which are the useful rays, are deflected so that they are projected in the same direction as the useful rays from lamp Y, as indicated by the solid lines, while the remaining rays from 35 this lamp are projected in other directions.
- From the foregoing, it will be evident that when one of the lamps G, Y and R is illuminated, a beam of light is projected from the refracting device L, and that the direction 40 in which this beam is projected is the same regardless of the lamp from which it emanates, the color of such beam depending upon which lamp is illuminated. I have found that when an observer is in the path 45 of this beam and at a considerable distance from the signal the entire surface of the device L appears to be illuminated.
- If desired, each surface P, P' and P^2 , may be made slightly concave or convex, to 50 spread each beam of useful rays projected by the signal. Such construction is particularly useful for signals which are to be used on railway curves.
- In the practical application of my invention to railway signaling systems, the lamps G, Y and R indicate "clear" "caution" and "stop" respectively, and may be controlled in any desired manner to indicate traffic conditions in advance of the signal, as will be 55 understood by those versed in the art of railway signaling. In this instance, this control is accomplished by a polarized relay X, which may be governed in any desired manner. Relay X is provided with three 60 neutral armature contacts designated 2, 3

and 4 respectively, and a polarized armature contact 5, which contacts control the supply of current from a battery Z to the lamps G, Y and R. The circuit for lamp G is from battery Z through wire 20, lamp G, wire 21, 70 polarized armature contact 5, wire 22, armature contact 2, wire 23, to battery Z. It will thus be seen that lamp G is illuminated only when relay X is energized in such directions as to cause polarized armature contact 5 to 75 swing to the left. The circuit for lamp Y is from battery Z, through wires 20 and 24, lamp Y, wire 25, armature contact 3, wire 26, polarized armature contact 5, wire 22, armature contact 2, and wire 23 to battery 80 Z. The lamp Y is therefore illuminated only when relay X is energized in such direction as to cause polarized armature contact 5 to swing to the right. The circuit for lamp R is from battery Z, through wires 20 and 85 27, lamp R, wire 28, lower point of armature contact 4, wires 29 and 23 to battery. Lamp R is therefore illuminated only when relay X is deenergized.

Referring now to Fig. 6, the signal in the form here shown comprises only two lamps G and R instead of three as in Fig. 1, and the light deflector L^a is in the form of a reflecting device instead of refracting device as in Fig. 1. This reflecting device comprises two sets of reflecting surfaces Q and Q' . The surfaces Q are so arranged and located that the rays from lamp G are projected back in the direction indicated in Figs. 6 and 7, while the surfaces Q' are so 100 arranged and located that the beam from lamp R is projected back in the same direction as shown in Fig. 8. The beam which is projected from the signal will of course be of one color or the other depending on 105 which lamp is illuminated.

The reflecting device L^a is preferably so designed, as shown in the drawings, that the entire beam of light from each source is reflected in the desired direction. That is, 110 each surface Q is preferably parallel to the direction of the beam projected from lamp R, and each surface Q' parallel to the direction of the beam from lamp G. Every ray from lamp G, then, strikes a reflecting surface Q, and every ray from lamp R strikes a reflecting surface Q' . All of the light from each pair of lenses K, K' is thus utilized, so that the efficiency of the signal is high.

It is to be particularly noted that in both 120 embodiments of my invention herein illustrated, a beam of parallel rays is projected from each light source to the light deflector, and the beam is then deflected in the desired direction without destroying the parallelism 125 of the rays. The deflector L or L^a , then, constitutes the ultimate light-emitting surface, so that no objective lens is required.

Although I have shown and described only 130 two forms of light signals embodying my

invention, it is understood that various changes and modifications may be made therein within the scope of the appended claims without departing from the spirit 5 and scope of my invention.

Having thus described my invention, what I claim is:

1. A signal comprising a plurality of sources of light, means for projecting 10 parallel rays of different colors from said sources to a common area, and means located in said common area for receiving and projecting rays from each of said sources of light in one common direction.
- 15 2. A signal comprising a plurality of sources of light, means for projecting parallel rays of different colors from said sources to a common area, controlling means for each source of light whereby any one of 20 said sources may be illuminated, and a deflector located in said common area for projecting rays from each source in one common direction.
- 25 3. A signal comprising a light deflector, a plurality of lamps, a plurality of lenses of different colors one for each of said lamps, each of said lenses being arranged to project parallel rays of colored light from its lamp to said deflector, said deflector being so constructed as to project rays from 30 each of said lamps in one and the same direction and to give the appearance, exteriorly of the deflector, that the deflector is fully illuminated.
- 35 4. A signal comprising a light deflector, a plurality of sources of light, means for projecting parallel rays of light from any one of said sources upon said deflector, said deflector comprising a plurality of reflecting 40 surfaces arranged to project rays from each source in the same given direction.
- 45 5. A signal comprising a light deflector, a plurality of sources of light, means for projecting parallel rays of light from any one of said sources upon said deflector, said deflector comprising a plurality of sets of reflecting surfaces, one set for each of said light sources, the surfaces of each set being arranged to project rays from the corresponding 50 source in a given direction.

6. A signal comprising a plurality of sources of light, means for projecting parallel rays of light from each source to a common area, and a deflector located in the said common area and constructed to project 55 rays from any one of said sources in the same given direction to give the appearance at one and the same point exteriorly of the deflector, that said deflector is fully illuminated.

7. A light signal comprising a plurality of sources of light, means associated with each source for projecting a beam of substantially parallel rays from the source upon a common area, and optical means located 65 at said common area for projecting rays from said several beams in one common direction while maintaining the rays from each source substantially parallel with each other.

8. A light signal comprising a plurality of sources of light, means associated with each source for projecting a beam of substantially parallel rays from the source upon a common area, and a reflecting device located at said common area and comprising a plurality of surfaces arranged to deflect the several beams in one common direction while maintaining the rays in each beam substantially parallel with each other.

9. A light signal comprising a plurality of sources of light, means associated with each source for projecting a beam of substantially parallel rays from the source upon a common area, and a reflecting device located at said common area and comprising a plurality of sets of reflecting surfaces one for each source, each set being arranged to deflect the beam from the corresponding source, and each reflecting surface being substantially parallel to the beam which is projected upon the reflecting device from another of said sources.

In testimony whereof I affix my signature in presence of two witnesses.

CLARENCE S. SNAVELY.
